David Hathaway, of Troy, N. Y.

Assignor to

Fisher Warren & Co, of Troy, N. Y.

Letters Patent, No. 1102, Dated May 17, 1859.

The schedule referred to in these Letters Patent and making part of the same.

To all, whom it may concern,

Be it known that I, David Hathaway, of the City of Troy, in the County of Rensselaer, and State of New York, have invented or produced a new and original design for a Door or Plate of a Stove; and I do hereby declare that the following is a full and exact description of the same, reference being had to the annexed photographic drawing, making a part of this Specification.

My new and ornamental design consists of a waved molding, C, arranged upon a panel of a door or plate of a stove so as to present substantially the same appearance as is represented in the annexed photograph.

What I claim as my invention or production and desire to secure by letters Patent is the ornamental design for a door or plate of a stove, as herein described and shown in the annexed photographic drawing.
